Primary Examiner — Erich G Herbermann*Assistant Examiner* — David Weir(74) Attorney, Agent, or Firm — Daniel M. Cohn; Howard M. Cohn(57) CLAIM

The ornamental design for a shopping cart as shown and described.

DESCRIPTION

FIG. 1 is a perspective view of a shopping cart showing my new design;

FIG. 2 is a front view thereof;

FIG. 3 is a back view thereof;

FIG. 4 is a left view thereof;

FIG. 5 is a right view thereof;

FIG. 6 is a top plan view thereof;

FIG. 7 is a bottom plan view thereof; and,

FIG. 8 is another perspective view thereof.

The broken lines depict portions of the shopping cart and form no part of the claimed design.
